UNITED STATES PATENT OFFICE.

JOHN H. MILLER AND GEORGE POHL, OF PLYMOUTH, INDIANA, ASSIGNEES TO KEY-STONE FOUNDRY COMPANY, OF PLYMOUTH, INDIANA, A CORPORATION OF INDIANA.

LAUNDRY STOVE.

Application filed May 25, 1922. Serial No. 563,479.

To all whom it may concern:

Be it known that we, JOHN HERMAN MILLER and GEORGE POHL, citizens of the United States of America, and residing at Plymouth, in the county of Marshall and State of Indiana, have invented certain new and useful Improvements in Laundry Stoves, of which the following is a specification.

The object of our invention is to produce 10 an improved laundry stove.

More specifically, one of our objects is to produce a laundry stove having a fire pot elongated to receive lengths of fire wood in common use, with a deflector-plate over the 15 rear of the fire pot to force the products of combustion to the front and sides of the stove top before passing out of the smoke flue.

A further object is to provide a water 20 heater capable of use as a deflector-plate in a stove of the type described.

Further objects and beneficial results of our invention will appear as the details of the preferred form are described, with reference to the accompanying drawings, in 25 which:

Fig. 1 is a plan view of a stove embodying our invention, with a part of the top removed to show the combined deflector-plate and water heater.

Fig. 2 is a side elevation of the stove showing a portion of the stove and the deflector-plate in section.

Fig. 3 is a front elevation of the stove.

Fig. 4 is a plan view of the combined deflector-plate and water heater.

Fig. 5 is a side elevation of the same.

Fig. 6 is a sectional elevation on the line 6—6, Figs. 4 and 5.

40 Figs. 7 and 8 are rear and front elevations, respectively, of the combined deflector-plate and water heater.

The stove is shown mounted on a base, 10, having legs, 11. The fire pot, 12, is shown 45 approximately rectangular in cross section, and longer from front to rear than from side to side, as clearly appears from a comparison of Figs. 2 and 3, and from the shape of the fire pot shown in dotted lines in Fig. 1.

50 The top, 13, of the stove is approximately square, and is somewhat longer and considerably wider than the firepot. The sides of the fire pot slope outward gently to the line, 14, from whence they spread rapidly to 55 where they meet the top near its edge.

A combined deflector-plate and water back or water heater, 15, is shown substantially covering the rear half of the fire pot. At the rear of member 15 inlet and outlet pipes, 16 and 17, are shown; and at the front 60 a projection, 18, reaches forwardly and upwardly to the stove top. The rear of the plate is nearly horizontal from side to side and besides are substantially horizontal from front to back; but the front of the plate is 65 curved upward in the middle, and thus the products of combustion are deflected toward the front and center of the stove top. An opening, 20, through the plate provides for the passage of some of the products of combustion directly through the plate to the middle of the rear of the stove top, and thus aids in heating the water in the hollow plate and at the same time provides for heating the 70 stove top over the plate.

75 As shown by dotted lines in Fig. 3, the front outside corners of the hollow plate are sloped substantially the same as the stove sides at that point, and thus the plate may rest firmly on the stove sides. The 80 front of the plate then forms an arch supporting projection 18 and the center of the stove top.

85 As the plate rounds in from the sides to the rear, it deflects a portion of the products of combustion through the narrow passage between the plate and the stove sides outward towards the edges of the rear portion of the stove top, while the products of combustion passing backward from the front of 90 the stove over the edges of the plate to smoke flue, 21, heat the portions of the rear of the stove top between the edges and the middle, heated through passage 20.

95 In this way it will be seen that we provide a stove with an elongated fire pot and square top and having a combined deflector-plate and water heater which will at the same time heat water and deflect the products of combustion so that they will heat the entire 100 stove top, and especially the front portion of it. If some such plate were not used the products of combustion tend to pass directly to the smoke flue, and so would heat the stove top but little, except for a small place 105 just in front of the flue.

110 It will be further noted that two regulable drafts are provided, one at 22, near the bottom, shown at the front, though not necessarily so located, and the other at 23, near

the top of the stove in front, as it needs to be for the best results in the combination shown. By regulating the lower draft, the rapidity of combustion is largely controlled, 5 and by regulating the upper draft, the proper amount of air may be admitted for completing combustion. At the instant if this completion of combustion the flame and products of combustion are in contact with 10 the top of the stove, and travel along a great portion of the top before reaching the smoke flue. Because of the shape of the plate, the passage between it and the sides of the stove, as well as the passage 20, the products 15 of the initial combustion passing up through these passages are spread out in sheets so that they will contact well with the draft from inlet 23 carrying the additional oxygen needed to complete combustion. The plate 20 is so curved that the side passages are widest at the points where they direct the gases towards the rear corners of the stove top which might otherwise tend to become cold. In this way the entire stove top is heated, 25 and much of the combustion takes place in contact with the top, so that the stove is very efficient for the purpose for which it is intended.

Having described our invention and the 30 preferred embodiment thereof, its purpose and the manner of its use will be understood without further description; and it will be understood also that the benefits of several features may be retained at least in 35 part with various modifications within the scope of the appended claims.

What we claim is:

1. In combination, in a stove, a fire pot, a 40 top, sides sloping outward and upward from the pot to the top, there being a smoke outlet in the rear of the stove top, and a deflector-plate between the pot and the smoke outlet, the front of said deflector-plate forming an arch having its ends resting on the 45 sloping sides and its center supporting the stove top.

2. In combination, in a stove, a fire pot, a flat top, sides sloping outward and upward from the pot to the top, there being a smoke 50 outlet at the rear of the top, a deflector-plate over the rear of the pot, the plate being concave on its under side with the concavity increasing toward the front, and the front forming an arch having its ends resting 55 on the sloping sides of the stove and its center supporting the middle of the top.

3. In combination, in a stove, a fire pot, a 60 top, sides sloping outward and upward from the pot to the top, there being a smoke outlet in the rear of the top, a hollow deflector-plate between the pot and the smoke outlet, the front wall of said hollow deflector-plate forming an arch having its ends resting on the 65 sloping sides of the stove and its center supporting the stove top, and inlet and out-

let pipes passing through the stove wall into the hollow deflector-plate.

4. In combination, in a stove, a fire pot, a flat top, sides sloping outward and upward from the pot to the top, there being a smoke 70 outlet at the rear of the top, a hollow deflector-plate over the rear of the fire pot, the plate being concave on its under side with the concavity increasing towards the front, 75 the front wall of the hollow plate forming an arch with its ends resting on the sloping sides of the stove and its center supporting the middle of the top, and inlet and outlet pipes passing through the wall of the stove 80 and into the hollow plate.

5. A laundry stove having a fire pot elongated from front to rear, a square top flat on its upper side and larger than the fire pot, sides sloping upward and outward from the pot to the top, there being a smoke outlet at the rear of the top, and a deflector-plate over the rear of the pot deflecting the products of combustion towards the front of the top and allowing their return between the sloping sides and the top. 85

6. A stove having a fire pot elongated from front to rear, a square top larger than the pot, sides sloping upward and outward from the pot to the top, there being a smoke outlet at the rear of the top, and a deflector-plate over the rear of the pot deflecting the products of combustion towards the front of the top, and forming an arch resting upon the sloping sides and supporting the top. 90

7. In a stove, a fire pot, a rectangular top larger than the pot, sides sloping upward and outward from the pot to the top, there being a smoke outlet at the rear of the top, and a deflector-plate over the rear of the pot, the said plate leaving a narrow passage 100 between itself and the stove sides at its sides and rear, the sides and rear of the plate being curved so that said passage is widest where it directs gases towards the rear corners of the stove top. 105

8. In a stove, a fire pot, a flat top, sides sloping upward and outward from the pot to the top, there being a draft inlet near the top of the front of the stove and a smoke outlet at the rear of the top, and a deflector-plate over the rear of the pot, having a central opening therethrough, the plate being higher in front of the opening than in the rear, and leaving a narrow passage between its sides and the sloping sides of the stove. 115

9. In a stove, a fire pot, a flat top, lower and upper draft inlets being located in the front of the stove, and there being a smoke outlet at the rear of the top, and a deflector-plate over the rear of the pot, the under side of said plate being substantially horizontal at the rear and concave at the front. 125

10. In a stove, a fire pot, a flat top larger than the fire pot, sides sloping upward and outward from the pot to the top, a smoke 130

- outlet at the rear, and a deflector plate over the rear of the pot, there being an opening through the plate, the front corners of the plate resting on the sloping sides and the rear corners being rounded off, and the under side of the plate being substantially horizontal at the rear and concave at the front. 45
11. In a stove, a fire pot, a flat top, sides sloping upward and outward from the pot to the top, there being lower and upper draft inlets at the front of the stove and a smoke outlet at the rear of the top, and a deflector-plate over the rear of the pot, the under side of said plate being substantially horizontal at the rear and concave at the front, and the front forming an arch with its ends resting on the sloping sides and its center supporting the middle of the stove top. 50
12. In a stove, a fire pot, a flat top, sides sloping upward and outward from the pot to the top, there being lower and upper draft inlets at the front of the stove and a smoke outlet at the rear of the top, a hollow deflector plate over the rear of the pot, the under side of said plate being substantially horizontal at the rear and concave at the front, the front wall of said hollow plate forming an arch with its ends resting on the sloping sides of the stove and its center supporting the middle of the top, and inlet and outlet pipes passing through the stove wall and into the said hollow plate. 55
13. In a stove, a fire pot elongated from front to rear, a top, sides sloping upward and outward from the pot to the top, there being lower and upper draft inlets at the front of the stove and a smoke outlet at the rear of the top, a hollow deflector-plate over the rear of the pot and sloping upward toward the front, said plate having a central opening therethrough elongated from front to rear, and there being a narrow passage be- 60
- tween the plate and the stove sides, and inlet and outlet pipes for said hollow plate. 65
14. In a stove, a fire pot, a flat top, sides sloping upward and outward from the pot to the top, there being lower and upper draft inlets at the front of the stove and a smoke outlet at the rear of the top, and a deflector-plate over the rear of the pot, the under side of said plate being substantially horizontal at the rear and concave at the front and the front forming an arch with its ends resting on the sloping sides of the stove and its center supporting the middle of the stove top, there being an opening through the plate elongated from front to rear, and there being narrow passages between the plate and the stove sides. 70
15. In a stove, a rectangular fire pot elongated from front to rear, a square flat top, sides sloping upward and outward from the pot to the top, there being upper and lower draft inlets at the front of the stove and a smoke outlet at the rear of the top, a hollow deflector-plate over the rear of the pot, the under side of said plate being substantially horizontal at the rear and concave at the front, the front wall of said hollow plate forming an arch having its ends resting on the sloping sides of the stove and its center supporting the middle of the top, there being an opening through the plate elongated from front to rear, and there being a narrow passage between the sides and rear of the plate and the stove sides, the passage being widest toward the rear corners of the stove, and inlet and outlet pipes passing through the rear wall of the stove and entering and supporting the rear of the hollow plate. 75

In testimony whereof we hereunto affix our signatures.

JOHN H. MILLER.
GEORGE POHL.
